UNITED STATES PATENT OFFICE

HOWARD M. BALLOU AND CHARLES A. JOSLIN, OF NORTH ATTLEBORO, MASSACHUSETTS

DESIGN FOR A HAND MIRROR OR LIKE ARTICLE

Application filed July 26, 1929. Serial No. 32,223. Term of patent 3½ years.

To all whom it may concern:

Be it known that we, HOWARD M. BALLOU and CHARLES A. JOSLIN, citizens of the United States, residing at North Attleboro, in the county of Bristol and State of Massachusetts, have invented a new, original, and ornamental Design for a Hand Mirror or like Article, of which the following is a specification, reference being had to the accompanying drawings, forming part hereof.

Fig. 1 of the drawings is a view of the ornamental back of a mirror or like article.

Fig. 2 is an edge view of the mirror.

Fig. 3 is a view of the top edge of the mirror.

We claim:

The ornamental design for a hand mirror, or like article as shown.

HOWARD M. BALLOU.
CHARLES A. JOSLIN.
